TURBINE BLADE TENON SPINNING MACHINE

John G. Morgan, Collingdale, and Joseph C. Bohan, Prospect Park, Pa., assignors to Westinghouse Electric & Manufacturing Company, East Pittsburgh, Pa., a corporation of Pennsylvania

Application December 16, 1936, Serial No. 116,106

7 Claims. (Cl. 78—53)

Our invention relates to turbine blade manufacture and it has for an object to provide a machine for spinning tenons of blades over the shroud element of a turbine blade assembly.

5 A further object of our invention is to provide a machine for spinning tenons of blades over a shroud strip of a blade assembly, the machine incorporating a support for the assembly and a spinning tool wherein the tool and the assembly 10 may be adjusted to effect spinning alignment of the working end of the tool and a tenon and wherein the spinning tool may be fed toward and away from a tenon.

15 A further object of our invention is to provide a machine for spinning the blade tenons over the shroud element of a turbine blade assembly wherein the spinning tool may be adjusted so that its axis extends normal with respect to the shroud element and wherein the spinning tool 20 may be fed toward and away from a tenon.

25 A further object of our invention is to provide a machine for spinning blade tenons over the shroud elements of a turbine blade assembly wherein the spinning tool is fed toward and away from a tenon and wherein an assembly is clamped in place with respect to its support in response to feeding motion of the spinning tool.

30 A further object of our invention is to provide a machine for spinning blade tenons over a shroud element of a turbine blade assembly wherein the support for a blade assembly is constructed and arranged to provide for adjustment thereof suitably to the dimensions of an assembly.

35 A further object of our invention is to provide a machine for spinning blade tenons over a shroud element of turbine blade assembly wherein the assembly is carried by a support mounted on a table and wherein the table is constructed 40 and arranged to facilitate the removal and assembly of a support with respect thereto.

45 These and other objects are effected by our invention as will be apparent from the following description and claims taken in connection with the accompanying drawings, forming a part of this application, in which:

Fig. 1 is a side elevational view of my improved heading machine;

50 Fig. 2 is a detail sectional view taken along the line II—II of Fig. 1;

Fig. 3 is a sectional view taken along the line III—III of Fig. 2;

55 Fig. 4 is a view similar to Fig. 1 but showing a different type of turbine blade assembly support;

Fig. 5 is a fragmentary plan view showing the type of assembly and support shown in Fig. 4;

Fig. 6 is a plan view showing the table and the type of working support shown in Fig. 1;

Fig. 7 is a detail view showing how the table 5 and the support may receive a further type of turbine blade assembly; and

Figs. 8 and 9 are detail views illustrating the principles of the spinning operation.

In the manufacture of elastic fluid turbines, it 10 is common practice to have turbine blade tenons extending through openings in shroud strips or elements, the tenons being headed over to firmly connect the shroud strips or elements to the blades. Heretofore, various ways have been used 15 to effect the step of fastening or heading. For example, the tenons may be hammered or rolled down, as in riveting, and then again the fastening may be effected by fusion. In accordance with the present invention, we provide a spinning 20 machine having a well-known type of head spinning tool, the machine incorporating arrangements for disposing the spinning tool in spinning alignment with respect to a tenon and for feeding the spinning tool to effect the spinning and heading 25 operation. The spinning tool is carried by a support, which, not only provides for the feeding motion, but may be adjusted both vertically and angularly to suit the requirements of a blade 30 assembly, it being desirable that the spinning 30 operation shall be effected with the axis of the spinning tool disposed normally with respect to the shroud element. Aside from these features 35 of adjustment of the spinning tool, the machine incorporates a clamp for holding a blade assembly in place during the spinning operation. In order to adapt the machine for different types of blade 40 assemblies, the assembly support is carried by a table, which provides, not only for adjustment of the support toward and away from the spinning 40 tool to suit the radial dimensions of blade assemblies, but it is constructed and arranged to provide for the assembly and removal of blade 45 assembly supports, whereby a support suitable for one type of blade assembly may be removed and another inserted.

Referring now to the drawings more in detail, there is shown a frame comprising vertical pedestals 10 and 11 carrying a table 12. A rotary spinning tool 13 is carried by the pedestal 10, the 50 spinning tool being manipulated, as hereinafter described, to spin over tenons 14 of blades 15 extending through openings 16 of shroud elements 17 of turbine blade assemblies.

The rotary spinning tool 13 is connected to an 55

arbor 13a driven by a motor 18, the motor, arbor and tool being mounted on a support, at 19, carried by the upper end of the post 20 guided for vertical adjustment by the pedestal 10.

The spinning tool 13 may be adjusted vertically by raising and lowering the post 20 to a desired extent, this operation being effected by any suitable means, for example, the post is shown as being raised and lowered by rack and pinion mechanism 21 operated by means of a hand-wheel 22.

Assuming suitable vertical adjustment of the spinning tool with respect to a blade assembly, then the tool may be angularly adjusted to place the spinning axis of the tool substantially at right angles to the outer surface of the shroud strip 17 so as to assure substantially symmetrical or uniform heads without the spinning tool gouging into the shroud or producing a head which is eccentric or which does not engage the shroud uniformly. To this end, the vertically adjustable post 20 has fastened to its upper end a yoke 23 having side plates 24, the tool support, at 19, having pivots or trunnions 25 extending through journal openings 26 formed in the side plates. The side plates also have slot or slots 27 arranged concentrically with respect to the openings 26 and having locking bolts or screws 28 extending therethrough, the locking bolts or screws being carried by the support, at 19.

If it is desired to arrange the axis of the spinning tool 13 so as to be normal with respect to the surface of the shroud strip element 17, then the locking bolts or screws 28 are loosened and the support, at 19, is moved angularly about the axis of the pivots 25; and, when the desired position is reached, the locking devices are tightened to clamp the support in adjusted position.

To provide for feeding of the spinning tool toward and away from a tenon, the support, at 19, is preferably formed in two parts, namely, the housing 30 and the guide or cradle 31, the housing 30 having a slide portion 32, preferably of T cross-section, fitting a guide groove or passage 33 formed in the guide or cradle 31, the guide portion 32 and the guide passage being arranged parallel to the axis of the spinning tool so that, by movement of the housing 30 along the guide, the tool may be adjusted in the direction of its axis toward and away from a tenon.

Feed motion may be imparted to the housing 30 by any suitable means. For example, the guide portion 32 is shown provided with a rack 34 meshing with a pinion 35, carried by the guide or cradle 31 and operatively connected to the lever 36. If the lever 36 is moved in one direction, the spinning tool 13 is advanced toward a tenon 14 and vice versa.

The machine is arranged for spinning blade tenons over shroud strips of blade assemblies of different types. In Fig. 1 the blade assembly A is shown as comprised by a disc 37 carrying blades 15 having tenons 14 extending through the openings provided in the shroud 17. In Figs. 4 and 5, the blade assembly B is comprised by a segmental blade holding member 38 of segmental or arcuate form, this type being particularly suitable for stationary or stator blading. In Fig. 7, there is shown a blade assembly C comprised by a spindle 39 having a plurality of spaced blade discs 40 carried thereby. In order that these different types of blade assemblies may be supported by the table 12, special supports are provided.

In Figs. 1 and 6 where the assembly A includes a blade disc, the assembly support in-

cludes a pair of blocks 41 having opposed V-notches 42 engaging the spindle element 43 for the disc, the blocks being drawn together by any suitable means, for example, the screws 44, to fit the element 43.

The block assembly is connected to the table 12 so as to provide for adjustment thereof toward and away from the spinning tool in any suitable manner. For example, the table 12 includes parts 45 and 46 which complementally provide a slot 47 whose opposed edges 48 are engaged by and fastened to the block assembly in any suitable manner, as by grooves 49 formed in the assembly and receiving the edges and by the device 50 for locking the assembly in position along the slot to suit the dimensions of a blade disc and the lengths of the blades carried thereby.

Where the blade assembly is comprised by a spindle with a plurality of blade discs thereon, as is the case with the assembly C in Fig. 7, then the blocks 41 have to be located about the spindle between adjacent discs; and, to provide for removal of the blocks 41 from the guide slot 47, the assembly of such blocks between adjacent discs and the re-assembly of the blocks encompassing the spindle between discs in the guide slot, the table part 46 is movable away from the part 45 to provide for removal and assembly of the block assembly in the slot. The table parts 30 are located in proper relative longitudinal position by means of pins 52 and 53 carried by the pedestals 10 and 11 and which fit complementary portions of circular openings 52a and 53a, formed in the table parts 45 and 46. The table 35 parts are fastened to the pedestals by means of screws 54.

Assuming that the blade assembly support of Figs. 1 and 6 is to be removed so that an assembly, such as shown in Fig. 7, may be inserted, the table part 46 is removed, whereupon the blocks 41 may be released from the guide slot 47 and arranged in encompassing relation with respect to the spindle between desired blade discs, as shown in Fig. 7, and, thereafter, the blocks encompassing the spindle may be reassembled with respect to the guide slot 47, the table part 46 being again fastened to the pedestals.

In Figs. 4 and 5, there is shown a support or fixture for a blade assembly of the sector type. In these views, the support such as shown in Figs. 1 and 6, is replaced by a supporting plate 56 and adjustable along the table 12 and clamped in position with respect to the groove 47 by means of the bolts 57 and the clamp bar 58. The arcuate holder 38 for the blades 15 is engaged at the back by a pair of spaced abutments 60 on the plate 56. Also, midway between the abutments 60, there is a third abutment 61, the latter being adjustable along the slot 61a to suit the curvature of the blade holding member. The axis of the abutment pin 61 is arranged substantially in the vertical plane of the spinning tool axis so that such pin is in line with the spinning thrust.

As shown in Figs. 1 and 4, the machine carries a clamp 63 which serves to hold a blade assembly firmly in place with respect to its support during the spinning operation, the clamp preferably being rendered effective by inward feed motion of the spinning tool toward a tenon. Accordingly, for example, the clamp 63 is carried by one end of the lever 64 supported at an intermediate point by a fulcrum 65, the other end of the lever having an inclined or cam surface 75

66 engaged by a roller 67 on the housing 30, the arrangement being such that, prior to engagement with the spinning tool 13 with a tenon 14 during feeding motion of the housing 30, the 5 roller 67 will have acted on the cam surface 66 to engage the clamp 63 with the blade holding member of a blade assembly so as to hold the latter firmly in position with respect to its support during the spinning operation. Upon retraction of the housing 30, the clamp is released thereby freeing the blade holding member so that the latter may be adjusted to bring another tenon into the vertical plane of the spinning tool axis. To facilitate adjustment of the apparatus 10 15 suitably to different blade assemblies, the fulcrum 65 is carried by a post 68 held in vertically adjusted position by a screw 69 and the lever has a plurality of fulcrum pin openings 70. Furthermore, the clamp 63 is carried by a stem 71 20 threaded to the lever to secure adjustment of the clamp with respect to the latter.

Apparatus made in accordance with our invention is operated as follows: If the tenons of blades of a blade disc are to be headed, the support arrangement shown in Figs. 1 and 6 is used. On the other hand, if the blade holding member is in the form of a sector carrying stationary blades, then the support shown in Figs. 4 and 5 is substituted for the first form of support, the table 30 12 being constructed and arranged to receive either type of support and either type of support being adjustable along the guide slot 47 of the table to suit the dimensional requirements of the blade holding member and the blades. Assuming that a blade assembly is mounted on its support and that the latter is adjusted to proper position along the table, then it is necessary to adjust the blade holding member to bring the tenons, one at a time, into the vertical plane 40 of the spinning tool axis. Assuming a tenon to be properly positioned for the spinning operation, then it is necessary to make such adjustments of the post 20 and the spinning tool support, at 19, as to bring the axis of the spinning tool into proper relation or spinning alinement with respect to a tenon. If the shroud strip is arranged at right angles to the tenons, the spinning tool axis is lined with a tenon axis to effect spinning alinement. With the work support and the 50 spinning tool support relatively adjusted in this way, the blade assembly is adjusted angularly to bring a tenon to be headed into spinning alinement with the spinning tool, whereupon the latter is fed inwardly to effect the spinning operation, 55 the clamping device being rendered effective to hold the blade assembly. Upon a tenon being headed over, the spinning tool and its support are retracted, the clamp being released during the back stroke. Next, the blade assembly is indexed or adjusted to bring the next tenon into spinning alinement and the operations just referred to are repeated and so on. Where the shroud strip 17 is arranged diagonally with respect to a tenon instead of at right angles, then 60 angular adjustment of the tool support, at 19, is necessary to produce spinning alinement of the tool and a tenon, the support being adjusted to cause the tool axis to intersect the axis of a tenon with such axis arranged substantially normal with respect to the shroud strip surface. Accordingly, in Fig. 4, the support, at 19, is 65 adjusted angularly about the pivots 25 and locked in position by means of the locking bolts 27 to hold the spinning tool in proper angular position 70 75 with respect to the shroud strip, this adjust-

ment being necessary in order that the tenon heads provided by spinning shall be symmetrical or engage the shroud strip in a uniform manner throughout their peripheral extent. As before, if, due to variations in dimensions, it should be necessary to effect vertical adjustment of the post 20, then this may be readily effected by operation of the handwheel 22. To provide for feeding and backing motion of the spinning tool, the support, at 19, is shown made in two parts, a 10 housing part 30 and a guide 31, the housing part, as well as the spinning tool carried thereby, being moved along the guide by means of the rack and pinion mechanism actuated by the hand lever carried by the guide 31. If necessary, the 15 clamp mechanism may be adjusted to suit different assemblies, the clamp may be adjusted with respect to the lever, the fulcrum may be raised and lowered, and the lever may be adjusted lengthwise with respect to the fulcrum pin. 20

While we have shown our invention in two forms, it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended claims.

What we claim is:

1. In a machine for heading blade tenons over a shroud strip of a turbine blade assembly, a frame including a table, a rotary spinning tool carried by the frame, said table including a pair of parts which complementally provide a slot extending toward the tool, a turbine blade assembly support carried by the table and adjustable along the slot suitably to the dimensions of a blade assembly, means for holding the assembly support in adjusted position along the slot, means 35 providing for movement of one of said table parts away from the other sufficiently to open the slot to facilitate assembly and removal of an assembly support with respect to the table, means providing for relative adjustment of the working end 40 of the spinning tool and a blade tenon to effect spinning alinement thereof, means carried by the tool support for feeding the spinning tool axially toward a tenon and for retracting it from the latter, and means responsive to feeding movement of the tool for clamping a blade assembly in place with respect to its support during each spinning operation.

2. In a machine for heading blade tenons over a shroud strip of a turbine blade assembly, a 55 frame including a table, a rotary spinning tool, a support for the spinning tool and carried by the frame, said table including a pair of parts which complementally provide a slot extending toward the spinning tool, a turbine blade assembly support carried by the table and adjustable along the slot suitably to the dimensions of a blade assembly, means for holding the assembly support in adjusted position, means providing for movement 60 of one of said table parts away from the other sufficiently to open the slot to facilitate the assembly and removal of a blade assembly support with respect to the table, means providing for vertical adjustment of the tool support with respect to the frame and for angular adjustment 65 thereof in the plane of the tool axis, means carried by the tool support for feeding the tool toward a tenon and away from the latter, and means responsive to feeding of the tool toward a 70 75

- tenon for clamping a blade assembly in place with respect to its support.
3. In a machine for heading blade tenons over a shroud strip of a turbine blade assembly, a frame, a rotary spinning tool, a support embodying guide and slide parts and the tool being carried by the slide part, a horizontally disposed turbine blade assembly support carried by the frame, a vertical post, a horizontal pivot between the upper end of the post and said guide part, means for holding the guide part in desired positions of angular adjustment with respect to the post, means for supporting the post from the frame and providing for vertical adjustment thereof and for holding it in vertically adjusted position, and means including a pinion carried by the guide part and meshing with a rack on the slide part for feeding the spinning tool toward a tenon and for retracting it from the latter.
20. 4. In a machine for heading blade tenons over a shroud strip of a turbine blade assembly, a frame, a rotary spinning tool, a support for the tool carried by the frame, means for adjusting the tool support angularly in the vertical plane of the tool axis and for holding it in adjusted position, a turbine blade assembly support carried by the frame and having an upper horizontal supporting surface, means carried by the spinning tool support for feeding the spinning tool toward a tenon and away from the latter, a lever, a fulcrum for the lever and carried by the frame, a gripping member connected to one end of the lever for holding a blade assembly in place with respect to said horizontal surface of the blade assembly support, and cam means cooperating with the other end of the lever and responsive to feeding motion of the tool to tilt the lever to cause the gripping member to clamp a blade assembly in place with respect to horizontal supporting surfaces.
40. 5. In a machine for heading blade tenons over a shroud strip of a turbine blade assembly, a frame, a rotary spinning tool, a tool support carried by the frame and including a slide part carrying the tool, a horizontally disposed turbine blade assembly support carried by the frame, means providing for vertical adjustment of the tool support and for angular adjustment thereof in the vertical plane of the tool axis, means for feeding the slide part and the tool toward a tenon and for retracting it from the latter, a lever, a fulcrum for the lever and carried by the frame,

a gripping device for holding the blade assembly in place with respect to its support, said gripping device including a jaw and means carried by one end of the lever for adjusting the jaw toward and from the latter, cam mechanism cooperating with the other end of the lever for rocking the latter about its fulcrum to cause said jaw to grip the blade assembly in place with respect to the support of the latter, said cam mechanism including an actuating element carried by said slide, and means providing for vertical adjustment of the fulcrum.

6. In a machine for heading blade tenons over a shroud strip of a turbine blade assembly, a frame, a rotary spinning tool, a support embodying guide and slide parts and the tool being carried by the slide part, a pivotal connection between the frame and said guide part and providing for adjustment of the latter in a plane transverse of the turbine blade assembly support and the blade assembly carried thereby, means for holding the guide part in desired positions of angular adjustment about said pivotal connection, and feed mechanism for imparting feed motion to the slide part to feed the spinning tool toward a tenon and for retracting it from the latter and including an operating element carried by said guide part.

7. In a machine for heading blade tenons over a shroud strip of a turbine blade assembly, a frame, a support embodying guide and slide parts, a turbine blade assembly support carried by the frame, an arbor carried by said slide part and extending toward the turbine blade assembly support, a spinning tool carried at the end of the arbor adjacent to the turbine blade assembly support, a motor for driving the arbor and carried by said slide part, a pivotal connection between the frame and said guide part and providing for adjustment of the latter in a plane transverse to the turbine blade assembly support and the blade assembly carried thereby, means for holding the guide part in desired positions of angular adjustment about said pivotal connection, and feed mechanism for imparting feed motion to the slide part to feed the spinning tool toward a tenon and for retracting it from the latter and including an operating element carried by said guide part.

JOHN G. MORGAN.
JOSEPH C. BOHAN.
